(57) **CLAIM**

The ornamental design for a gravy separator, as shown and described.

DESCRIPTION

FIG. 1 is a perspective view of a gravy separator showing our new design.

FIG. 2 is an exploded view thereof.

FIG. 3 is a top perspective view thereof, the vessel portion shown separately for clarity of illustration.

FIG. 4 is a front view of FIG. 3.

FIG. 5 is a side view of FIG. 3.

FIG. 6 is a rear view of FIG. 3.

FIG. 7 is a bottom plan view of FIG. 3.

FIG. 8 is a top plan view of FIG. 3.

FIG. 9 is a bottom perspective view of FIG. 3.

FIG. 10 is a top perspective view of FIG. 3.

FIG. 11 is a top perspective view thereof, the strainer portion shown separately for clarity of illustration.

FIG. 12 is a top plan view of FIG. 11.

FIG. 13 is a front view of FIG. 11.

FIG. 14 is a side view of FIG. 11; and,

FIG. 15 is a rear view of FIG. 11.
